UNITED STATES PATENT OFFICE.

JOHN H. THOMAS, OF MOUNT VERNON, NEW YORK.

SURGICAL-BANDAGE FASTENER.

1,313,138.

Specification of Letters Patent. Patented Aug. 12, 1919.

Application filed January 22, 1917. Serial No. 143,763.

To all whom it may concern:

Be it known that I, JOHN H. THOMAS, a citizen of the United States, residing at Mount Vernon, in the county of Westchester and State of New York, have invented 5 certain new and useful Improvements in Surgical-Bandage Fasteners, of which the following is a specification.

This invention relates to surgical appliances and more particularly to bandage fasteners and the primary aim of the invention is to provide means whereby a gauze bandage may be more conveniently, securely, and expeditiously applied than by the ordinary 10 methods. In applying bandages by the ordinary methods the exercise of considerable skill is required in reversing the bandage and in overfolding the same and carrying it about the part to be bandaged in the various 15 directions found necessary in each particular case and unless this operation is skilfully performed there is likelihood that the bandage will work loose or become otherwise displaced. The present invention, therefore, 20 has as its object to provide an appliance in the use of which a gauze bandage may be quickly and conveniently applied and reversed, overturned, and carried at different angles to suit the particular case 25 without any particular attention being paid to the temporary holding in place of the bandage at the fold or point of reversal.

Another aim of the invention is to provide an appliance of the class described which will 30 constitute a means for securing the end of the bandage without the necessity of stitching or otherwise securing the same in place and which will at the same time permit of the ready removal of the bandage when it is desired 35 to apply a fresh one.

Another aim of the invention is to provide an appliance for the purpose heretofore stated which may be applied to practically any portion of the anatomy and which will 40 conform to the shape of the part to which it is applied without any discomfort to the patient.

Incidentally, the invention aims to so construct the appliance that the same will 45 neither by undue rigidity or weight in any way cause discomfort to the patient to whom the bandage is applied.

Further, the invention aims to provide an 50 appliance of this nature which shall be in the form of a flexible or pliable strip from

which lengths may be cut by the surgeon suitable to the member or area to be bandaged so that it is unnecessary to manufacture the appliance in different lengths but, on the other hand, a strip constructed in accordance with the invention and of any desired length may be carried by the surgeon and portions thereof severed when desired for use.

In the accompanying drawings: 65

Figure 1 is a perspective view of the appliance embodying the present invention and a bandage secured thereby, the same being illustrated as applied to the head of a patient;

Fig. 2 is a detail vertical transverse sectional view on the line 2—2 of Fig. 1 through the appliance and the bandage;

Fig. 3 is a plan view of a portion of the strip comprising the invention; 70

Fig. 4 is a horizontal sectional view illustrating an arrangement of the strip;

Fig. 5 is a vertical longitudinal sectional view through the strip;

Fig. 6 is a fragmentary perspective view 80 of a portion of the strip shown in Fig. 3 arranged to encircle a part to be bandaged;

Fig. 7 is a detail transverse sectional view through the strip;

Fig. 8 is a view similar to Fig. 5 illustrating a modified form of the invention; 85

Fig. 9 is a perspective view illustrating a further modification.

The appliance embodying the present invention is in the nature of a strip indicated 90 by the numeral 1 and this strip is relatively thin and may be of any suitable width and of any desired length, the strip being formed of any material suitable for the purpose and possessing the desired degree of pliability.

such, for example, as aluminum or copper, it being understood, however, that any material possessing the desired properties may be employed for the purpose. At intervals in its length the strip is formed with integral 100 piercing fingers, indicated by the numeral 2, and as shown in Figs. 5 and 6 these fingers are preferably of lanceolate form and are relatively narrow and in forming the said fingers the same are struck up from the strip 1 alternately from opposite side of the longitudinal middle of the strip and all are caused to initially assume positions in a common plane perpendicular to the plane of the body of the strip and coincident with the said longitudi- 105

nal middle of the strip. In other words, the fingers are formed from material struck up from the strip itself and the bases of the fingers are located in alinement at the longitudinal middle of the strip, the fingers, as before stated being struck up alternately from the strip at opposite sides of the said middle, as clearly shown in Fig. 3 of the drawings. As stated, the fingers are of lanceolate form and near its base each finger is slightly narrowed, as at 3, so that after the fingers have pierced the gauze bandage in the act of applying the bandage after the appliance has been placed in position against the part or member about which the bandage is to be passed the threads of the bandage will, in tending to resume their normal condition, sink into the shallow recesses formed by narrowing the lower portions of the fingers whereby to prevent accidental slipping of the said bandage from the said fingers. Being of lanceolate form the ends of the fingers 2 are sharply pointed and the said ends or tips, indicated by the numeral 4, are hardened in any suitable manner so that while the fingers below their tip ends are pliable due to the inherent pliability of the metal from which the strip is formed, their said tip ends will not be liable to be accidentally overturned or blunted as the gauze bandage is forced downwardly over the fingers. For a purpose to be presently explained the strip 1 is formed with perforations or slots 5 and these perforations or slots are arranged in two series extending longitudinally of the strip, the perforations or slots of the two series being alternately located opposite and close to the bases of alternate ones of the bandage piercing fingers of the appliance. In other words, the strip is formed with one of the perforations or slots 5 opposite the base of each finger, the said perforation being located at that side of the longitudinal median line of the strip opposite the side from which the finger is struck. Each perforation or slot 5 is of dimensions to permit of insertion therethrough of one of the piercing fingers.

A surgeon wishing to apply a bandage and secure the same in place by the use of an appliance embodying the invention will cut from the strip a suitable length thereof depending, of course, upon the nature of the case to be treated and this may be readily accomplished inasmuch as the strip is comparatively thin and of relatively soft and pliable metal and as an aid to the surgeon in determining the length to be cut the strip may be provided at suitable intervals at or adjacent one or both edges with scale marks 6 representing units of linear measurement as, for example, inches and fractions thereof. After having removed from the strip a suitable length thereof, the surgeon disposes against the part to be bandaged a sufficient

length of bandage or any other dressing which will prevent direct contact of the strip with the skin which would be likely to cause discomfort to the patient and he then disposes against this protective strip the appliance which then constitutes the portion of the strip 1 which he has removed. He next forces one end of the gauze bandage to be applied direct over the fingers 2 so that the fingers will pierce the said bandage. He then proceeds to wind the bandage in the usual manner, forcing the same downwardly over the fingers each time the bandage crosses the appliance. Whenever it is desired to reverse the bandage or to overfold the same or carry the same at an angle to the wrappings already made, this may readily be accomplished by merely reversing the direction in which the bandage is carried immediately after it has been pierced by the fingers, the bandage adjacent the fold which provides for such reversal being, of course, again pierced by the fingers. It will be understood that this may be repeated any desired number of times and at the time of reversal the bandage may be carried at any desired angle after the second penetration thereof by the fingers 2. After the bandage has been properly applied the other end thereof is brought across the appliance and forced downwardly to be pierced by the fingers 2 and all of the said fingers are then turned down in the direction of the said end of the bandage, thereby firmly securing the end in place as also all of the folds and turns previously made therein.

While the fingers 2 are preferably of the form shown in Figs. 5 and 6 of the drawings, it will be understood that they may be substantially triangular and relatively narrow, as indicated by the numeral 7 and as clearly shown in Fig. 8 of the drawings although the form of finger previously illustrated is to be preferred as the narrowed lower portion thereof serves to prevent accidental slipping of the bandage from the said fingers. It will also be understood that fingers having various other marginal contours may be struck up from the strip 1 if desired.

When it is desired to remove the bandage for the purpose of applying a fresh one or when the bandage is to be finally removed, this may be readily accomplished without discomfort to the patient by merely bending up the fingers 2 to their initial or normal condition and then proceeding to unwind the bandage as would ordinarily be done.

When it is desired to adapt the appliance about a limb or about the head this may be readily accomplished by first cutting off the desired length from a roll or other package of the strip 1 and then disposing the severed length to surround the limb or head, as the case may be, with one end of the said length.

overlapping the other whereupon the end finger at the extremity of the overlapped end of the said length of the strip may be inserted through the perforation 5 at the 5 extremity of the overlapping end of the said length of the strip and bent down, as indicated by the numeral 2' and as clearly shown in Figs. 1 and 6 of the drawings. In this manner the ends of the strip are joined 10 so that the strip will be held about the part to which it is applied and while this particular finger 2' is thus rendered useless in securing the bandage in place, nevertheless, the series of bandage piercing fingers will 15 not be interrupted for the piercing finger next adjacent the perforation through which the finger 2' is inserted, for this purpose, takes the place of the said finger 2'.
 Under some conditions, as for example, 20 in applying a bandage to the shoulder, it will be found preferable to make use of that form of the invention shown in Fig. 9 of the drawings. In this form of the invention any suitable number of lengths of the strip 25 1, indicated by the numeral 8, are assembled with their ends overlapping a short distance and are connected by means of pivots 9 passed through one corner of each strip. Thus one strip or length may be caused to 30 assume a position out of alignment with the next adjacent strip or length to suit the case and the conditions under which the appliance is to be employed.

While the appliance has been illustrated 35 and described herein as in the nature of a pliable strip it will be understood, of course, that inasmuch as the strip constitutes the base of the fastener, a base of any other type may be employed, such for example, as 40 a disk or a strip of a definite length or a plate of definite dimensions without departing from the spirit of the invention. It will also be understood that in the first illustrated and described form of the invention 45 the narrowed portions of the fingers 2 re-

sult in effect in the formation of shoulders which may be more defined than as illustrated in the drawings if desired. Also if desired the base of the fastener may be made sufficiently rigid as to constitute a splint so 50 that it will serve two purposes.

Having thus described the invention, what is claimed as new is:

1. A bandage fastener including a pliable base, and bandage piercing fingers projecting from one face thereof, the said base being formed at intervals with slots, whereby when the base has been applied to encircle a part to be bandaged one of the fingers at one end of the base may be engaged in one 60 of the slots at the other end of the base to hold the fastener in place.

2. A bandage fastener including a flexible base formed at intervals with openings, and pliable bandage piercing fingers projecting from one face of the base, whereby when the base has been applied to encircle a part to be bandaged one of the fingers at one end of the base may be engaged through 65 one of the openings at the other end of the base and bent down to hold the ends of the base connected.

3. A bandage fastener including pliable base sections connected for relative angular adjustment, and pliable bandage piercing 75 fingers projecting from one face thereof.

4. A bandage fastener including a base having bandage piercing fingers struck up therefrom and in a longitudinal series, the said fingers being pliable and the said base 80 being formed with two series of slots extending at the opposite sides of the series of fingers, the slots of the two series being arranged in staggered relation and each slot being located opposite an opening formed 85 by stamping up the finger next adjacent the slot.

In testimony whereof I affix my signature.

JOHN H. THOMAS. [L.S.]
